SOUND MOTION-PICTURE CAMERA

Walter H. Bach, Los Angeles, and Robert L. George, Torrance, Calif., assignors to Berndt-Bach, Incorporated, Los Angeles, Calif., a corporation of California

Application December 26, 1950, Serial No. 13,596

Term of patent 14 years

(Cl. D31—1)

To all whom it may concern:

Be it known that we, Walter H. Bach and Robert L. George, both citizens of the United States of America, residing at Los Angeles, in the county of Los Angeles, State of California, and Torrance, in the county of Los Angeles, State of California, respectively, have invented a new, original, and ornamental Design for a Sound Motion Picture Camera, of which the following is a specification, reference being had to the accompanying drawing, forming a part hereof.

Figure 1 is a perspective view of the front and right side of a sound motion picture camera, showing our new design;

Figure 2 is an elevational view of the left side of the camera shown in Figure 1;

Figure 3 is a rear elevational view thereof; and Figure 4 is a top plan view thereof.

We claim:

The ornamental design for a sound motion picture camera, substantially as shown and described.

WALTER H. BACH.
ROBERT L. GEORGE.
